UNITED STATES PATENT OFFICE

169,662

LAMP

Irmi Ann Gross, New York, N. Y.

Application February 18, 1953, Serial No. 23,676

Term of patent 7 years

(Cl. D48—20)

To all whom it may concern:

Be it known that I, Irmi Ann Gross, a citizen of the United States of America, residing in New York city, county of New York, and State of New York, have invented a new, original, and ornamental Design for a Lamp, of which the following is a specification, reference being had to the accompanying drawing, forming part thereof, wherein,

The opposite side of the lamp, not shown, is identical in appearance to the side shown in Figure 1.

I claim:

The ornamental design for a lamp, substantially as shown and described.

IRMI ANN GROSS.
